UNITED STATES PATENT OFFICE.

JULIUS WEINBERGER, OF NEW YORK, N. Y., ASSIGNOR TO RADIO CORPORATION OF AMERICA, A CORPORATION OF DELAWARE.

RADIO RECEIVING SYSTEM.

Application filed March 3, 1921. Serial No. 449,469.

To all whom it may concern:

Be it known that I, JULIUS WEINBERGER, a citizen of the United States, residing in the borough of Manhattan, city, county, and 5 State of New York, have invented certain new and useful Improvements in Radio Receiving Systems, of which the following is a specification.

This invention relates to radio communication and aims to provide means for eliminating interference.

Since all electromagnetic waves reaching a receiving antenna produce an effect to a greater or less extent, it is necessary to 10 adopt means for eliminating or reducing the effects of all waves but the ones proceeding from the desired sending station. Various means have been proposed for this purpose, the most common probably involving the 15 tuning of the antenna and receiving circuits to the wave length to be received. This is more or less successful when the desired wave and the interfering waves are of the same order of strength and of widely different 20 frequencies, but it is of little use when the interfering waves are much stronger than the desired waves and of nearly the same frequency. Interference of this nature 25 is encountered when the receiving station is near to an interfering transmitting station as compared to its distance from the transmitting station being received.

The aim of my invention is to overcome relatively strong interference of this kind, 30 though it may be used for the prevention of interference regardless of the strength of the interfering current.

The invention can be applied in various ways but I have shown by way of example 35 illustrative embodiments on the accompanying drawings in which:

Fig. 1 represents diagrammatically a receiving system and Fig. 2 is a modification thereof.

Referring to the drawing, 1 represents an 40 antenna, and 2 a receiving circuit tuned to the signal frequency. The receiving circuit comprises the usual coupling coil 3, loading coil 4 and tuning condenser 5 coupled to an 45 ordinary detector circuit 6 comprising an inductance 7 and tuning condenser 8, by means of variable coupling coils 9, 10. The coupling coils are both connected at one end 50 to a condenser 11, the other side of which 55 is connected to the receiving and amplifier

circuit. In order to eliminate an interfering signal of a frequency f the mutual inductance M between the coupling coils 9, 10 and the capacity C of the condenser 11 is so chosen or adjusted that the relation between 60 these values is represented substantially by the following equation:

$$4\pi^2 f^2 = \frac{1}{MC} \quad (1)$$

65

The modification shown in Fig. 2 differs from Fig. 1 in that the receiving circuits are somewhat simplified by eliminating the circuit 3, 4, 5 and coupling the antenna coil 12 directly to the detector circuit. The relation of the mutual inductance between coils 12 and 10 and the capacity of condenser 11 is chosen or adjusted in substantially the same manner as described with reference to Fig. 1.

75

The elimination of the interfering signal of frequency f may be explained as follows:

If a generator of alternating current of frequency f connected across the lines of the receiver circuit connected to the coil 9 and 80 the condenser 11 sends a circuit i through the circuit 9, 11, then this circuit produces a voltage e_0 across the condenser 11 of capacity C which is given by the expression:

85

$$e_0 = \frac{i}{2\pi f C}$$

The voltage e_M generated in coil 10 by current i passing through coil 9 due to the mutual inductance M between the coils is 90 given by the expression:

$$e_M = -2\pi f M i$$

Now if it is desired to have zero voltage 95 across the circuit 10, 11 for the frequency f , the necessary condition is that $-e_M = e_0$ or

$$2\pi f M i = \frac{i}{2\pi f C}$$

100

which reduces to

$$4\pi^2 f^2 = \frac{1}{MC}$$

Therefore if it is desired to eliminate an 105 interfering frequency of f this can be done by choosing or adjusting the mutual inductance and capacity in accordance with equation (1).

However, when this is done the voltages 110

across inductance 10 and condenser 11 will not be equal for the signal frequency, and the amplifier circuit will respond thereto.

The equations given above are based on the condition that the losses in condenser 11 are negligible and in actual trial it has been found that the elimination of interference of a high order of magnitude can be accomplished with ordinary commercial condensers.

Having described my invention what I claim is:—

1. In radio telegraphy, means for eliminating interference, comprising primary and secondary circuits, a pair of connections across the primary and secondary circuits, each connection comprising two portions consisting of capacity and inductance in series, one of said portions being common to both connections and the other portions being arranged to couple the primary and secondary circuits, said portions being relatively adjustable to substantially eliminate interference.
2. In radio telegraphy, means for eliminating interference, comprising primary and secondary circuits, adjustable coupling coils for varying the coupling between the primary and secondary circuits and a condenser in series with both of the coupling coils and connected to the primary and secondary circuits, the mutual inductance of said coupling coils and the capacity of said condenser being relatively adjusted to substantially eliminate interference.
3. In radio telegraphy, means for elimi-

nating interference comprising primary and secondary circuits, coupling coils between the primary and secondary circuits and a condenser in series with both of the coils and connected to the primary and secondary circuits, the mutual inductance between the coils and the capacity of the condenser being adjusted so that their relation is substantially expressed by the equation

$$4\pi^2 f^2 = \frac{1}{MC}$$

where f is the interfering frequency.

4. In radio telegraphy the combination of a primary circuit and a secondary circuit tuned to the signal frequency and means for eliminating interference on the secondary circuit, comprising coupling coils between the primary and secondary circuits and a condenser in series with both of the coils and connected to the primary and secondary circuits, the mutual inductances of said coupling coils and the capacity of the condenser being relatively adjusted to substantially eliminate interference on the secondary circuit.

5. In radio signaling apparatus having a primary and a secondary circuit, a coupling coil having one winding connected in said primary circuit, and another winding connected in said secondary circuit, a variable capacity in series with both said windings, and means for varying the coupling between said windings.

JULIUS WEINBERGER.
